UNITED STATES PATENT OFFICE.

HENRY W. GRIFFIN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,211,141.

Specification of Letters Patent. Patented Jan. 2, 1917.

Original application filed January 27, 1913, Serial No. 744,367. Divided and this application filed June 30, 1913, Serial No. 776,483. Renewed October 19, 1916. Serial No. 126,626.

To all whom it may concern:

Be it known that I, HENRY W. GRIFFIN, a citizen of the United States, residing at New York city, in the county and State 5 of New York, have invented certain new and useful Improvements in Railway Signaling, of which the following is a specification.

My invention relates to railway signaling 0 and particularly to signaling for stretches of single track over which traffic moves in both directions.

The present application is a division of my co-pending application, filed January 5 27, 1913, Serial No. 744,367, for railway signaling.

I will describe two forms of railway signaling embodying my invention and will then point out the novel features thereof 0 in claims.

In the accompanying drawings, Figure 1 is a diagrammatic view showing a stretch 5 of single track having applied thereto one form of railway signaling embodying my invention. Fig. 2 is a view similar to Fig. 1, but showing a modification of the signaling shown in Fig. 1.

Similar reference characters refer to similar parts in each of the several views.

Referring first to Fig. 1, A designates the track rails of a stretch of single track over which traffic moves in both directions. The track rails of the stretch A are electrically separated from the adjoining track 5 rails by insulations 27. The stretch A is provided with a track circuit comprising the track rails, a source of current connected with the track rails adjacent the middle of the stretch, and two track relays R and R' connected with the track rails adjacent the ends of the stretch respectively. As here shown, the source of current is a transformer T, whose secondary is connected with the track rails and whose primary is connected with a suitable source of alternating signaling current, which source is not shown in the drawing. Inasmuch as the signaling current is alternating in character, the track relays R and R' are preferably of a type responsive only 50 to alternating current; as here shown, these relays are each of the vane type. With the track circuit arranged as just described, it is well understood that when a car or train enters the stretch from either end, 55 it immediately opens the track relay adjacent that end, but the track relay adjacent the other end is not opened until the car or train reaches a point near the point of connection of the source of signaling current with the track rails, as indicated on the drawing. After the car or train has passed a short distance beyond the point of connection of the source of signaling current with the track rails, the relay in 60 the rear of the car or train again closes, but the other relay remains open until the car or train leaves the stretch. The point at which the relay in the rear of the car or train closes is substantially the same 65 as the point at which this relay is opened by a car or train moving in the other direction.

Traffic into the stretch A from opposite directions is governed by two end signals 75 S and S', located respectively adjacent the ends of the stretch. I also provide two intermediate signals B and B' for the stretch A. Signal B is located in advance of signal S, but in the rear of the point 80 at which an eastbound car or train causes track relay R' to open; and, similarly, signal B' is located in advance of signal S' but in the rear of the point at which a westbound car or train passing through the 85 stretch causes track relay R to open. As here shown, the distance of intermediate signals B and B' from the adjacent end of the stretch is about one-quarter of the distance from the adjacent end of the 90 stretch to the middle, although I do not wish to limit myself to this particular location of these intermediate signals. Each of the four signals is adapted to indicate "stop" and "proceed"; as shown in Fig. 1, 95 all four of the signals are of the semaphore type, but it is understood that other types of signals may equally well be employed.

Each of the end signals S and S' is controlled by both track relays R and R'; intermediate signal B is controlled by track relay R' and intermediate signal B' is controlled by track relay R. I will now explain the circuits by which this control of the signals is accomplished. Track relay R' controls a signal circuit which comprises two branches for the control respectively 10 of signal S and signal B. The circuit for signal B is from source of current 11 (here shown as being a direct current battery), through contact 12 of relay R', wires 13 and 15, signal B, wire 16, common wire O to battery 11. The branch of this signal circuit which controls signal S is from wire 13 through wire 17, contact 18 of relay R, wire 19, signal S, wire 20, common wire O to battery 11. The signal circuit for 20 the control of signals S' and B' is similar to that just traced for signals S and B; consequently, it need not be traced herein.

The operation of the apparatus shown in Fig. 1 is as follows: Assume that a car or 25 train passes through the stretch A from west to east. As this car or train enters the stretch, it immediately opens track relay R, thereby causing signals S, B' and S' to change to stop indication. The opening of 30 relay R does not, however, effect signal B and this latter signal continues to indicate proceed until after it has been passed by the car or train. When the car or train reaches the point near the middle of the 35 stretch, as indicated on the drawing, it causes track relay R' to open and the opening of this relay causes signal B to change to stop indication. When the car or train reaches a point a short distance beyond the 40 middle of the stretch, that is, substantially the point at which a westbound car or train opens relay R, track relay R closes, so that signal B' then changes to proceed indication. Track relay R', however, remains open until 45 the car or train leaves the stretch, consequently, signals S', S and B, continue to indicate stop until the car or train leaves the stretch.

The operation of the apparatus for the 50 passage of a westbound car or train through the stretch is similar to that just explained. If two cars or trains moving in opposite directions should enter the stretch A at the same time, it is obvious that each 55 car or train would receive a proceed indication at signals S and S' respectively, hence both cars or trains would be authorized to proceed into the stretch. Both signals B and B' would, however, be changed at once 60 to indicate "stop," hence, both cars or trains would receive a stop indication as they approach these signals. It will be seen, therefore, that it is impossible to bring two cars or trains together in the stretch A.

Each intermediate signal B, B' is preferably located a considerable distance in the rear of the point at which a car or train proceeding through the stretch from the adjacent end causes the track relay at the opposite end of the stretch to open. This 70 location of the intermediate signals is preferable for several reasons; first, so that the distance between each end signal and the adjacent intermediate signal can be made uniform for both long and short blocks; 75 second, so that a car or train will not be required to back up too far in case it finds the intermediate signal indicating "stop"; third, so that, the distance between the end signals and the adjacent intermediate signals being short, when a car or train approaches an intermediate signal the driver will not be under the impression that he is approaching a new block section. 80

Referring now to Fig. 2, the apparatus 85 and circuits here shown are similar to those shown in Fig. 1. In Fig. 2, however, the intermediate signals, which are here designated by the reference characters C and C', respectively, are of the light type instead 90 of the semaphore type. Each intermediate signal C and C' comprises two electric lamps r and g. These lamps are provided with lenses or glasses of different colors. For example, each lamp r may be provided 95 with a red lens or glass, and each lamp g may be provided with a green lens or glass. In accordance with the usual practice, when the red lamp r of either of these signals is illuminated and the green extinguished, the 100 signal indicates "stop," and when the green lamp is illuminated and the red extinguished the signal indicates "proceed." Each signal C and C' is controlled by a signal relay D or D', the control of each 105 of these signals being such that when the corresponding signal relay is energized, the green lamp g is illuminated and the red lamp r is extinguished, but when the corresponding signal relay is deenergized the 110 red lamp r is illuminated and the green lamp g is extinguished. The circuit for the green lamp g of signal C is from battery 28, through the front point of contact 29 of relay D, wire 30, lamp g, wire 31, common 115 wire O to battery 28; the circuit for red lamp r of signal C is from battery 28, through the back point of contact 29 of relay B, wire 32, lamp r, wire 31, common 120 wire O to battery 28. The circuits for the 125 lamps r and g of signal C' are similar to those just traced for signal C.

Track relay R' controls a signal circuit which is provided with two branches for the control respectively of signal relay D 130 and signal S; and track relay R similarly controls a signal circuit which is provided with two branches for the control respec-

tively of signal relay D' and signal S'. The operation of the apparatus shown in Fig. 2 will be evident from the explanation given hereinbefore of the operation of the 5 apparatus shown in Fig. 1.

Although I have herein shown and described only two forms of railway signaling embodying my invention, it is understood that various changes and modifications may 10 be made therein within the scope of the appended claims, without departing from the spirit and scope of my invention.

Having thus described my invention, what I claim is:

15 1. In combination, a stretch of railway track, a source of alternating signaling current connected with the track rails adjacent the middle of the stretch, two track relays connected with the track rails adjacent the 20 ends of the stretch respectively, two end signals located adjacent the ends of the stretch respectively, two intermediate signals located respectively in advance of the end signals but in the rear of the point at 25 which a car or train passing through the stretch from the adjacent end opens the track relay at the other end, two signal circuits one controlled by each track relay, each signal circuit comprising two branches 30 for the control respectively of the two signals on the opposite side of the source from the track relay, the said branch for each end signal being controlled also by the track relay adjacent the corresponding end.

35 2. In combination, a stretch of railway track, a source of signaling current connected with the track rails adjacent the middle of the stretch, two track relays connected with the track rails adjacent the ends 40 of the stretch respectively, two end signals for the stretch located adjacent the ends of the stretch respectively, two intermediate signals located respectively on opposite sides of the source, two signal circuits one 45 controlled by each track relay, each signal circuit comprising two branches for the control respectively of the two signals on the opposite side of the source from the track relay, the said branch for each end signal 50 being controlled also by the track relay adjacent the corresponding end.

3. In combination, a stretch of railway track, two track relays connected with the track rails adjacent the opposite ends of the 55 stretch and arranged to be opened successively by a car or train passing through the stretch, the relay first opened remaining open until after the other relay has opened, means for energizing said relays, two end 60 signals located respectively adjacent the ends of the stretch, two intermediate signals located respectively in advance of the end signals but in the rear of the point at which a car or train passing through the

stretch from said end causes the track relay at the opposite end of the stretch to open, and two signal circuits one controlled by each track relay, each signal circuit comprising two branches for the control respectively of the two signals adjacent the opposite end of the stretch from the track relay which controls the signal circuit, the branch for each end signal being controlled also by the track relay adjacent such end signal.

4. In combination, a stretch of railway track, two track relays connected with the track rails adjacent the opposite ends of the stretch and arranged to be opened successively by a car or train passing through the stretch, the relay first opened remaining open until after the other relay has opened, means for energizing said relays, two end signals located respectively adjacent the ends of the said stretch for governing the entrance of cars or train into the stretch, two intermediate signals located respectively in advance of the end signals but in the rear of the point at which a car or train passing through the stretch from said end causes the track relay at the opposite end of the stretch to open, a signal relay for each intermediate signal for the control thereof, two signal circuits one controlled by each track relay, each signal circuit comprising two branches for the control respectively of the end signal at the opposite end of the stretch from the track relay and of the signal relay for the intermediate signal adjacent the opposite end of the stretch from the track relay, the said branch for each end signal being controlled also by the track relay adjacent such end signal.

5. In combination, a stretch of single track over which traffic moves in both directions, two track relays connected with the track rails adjacent the ends of the stretch respectively and arranged to be opened successively by a car or train passing through the stretch, the relay first opened remaining open until after the other relay has opened, means for energizing said relays, two end signals located respectively adjacent the ends of the stretch, two intermediate signals located respectively in advance of the end signals but in the rear of the point at which a car or train passing through the stretch from said end causes the track relay at the opposite end of the stretch to open, each intermediate signal comprising two electric lamps adapted when illuminated to indicate respectively stop and proceed, a signal relay for each intermediate signal, circuits for the lamps of each signal controlled by the corresponding signal relay and so arranged that when the relay is energized the proceed lamp is illuminated and that when the signal relay is deenergized the stop lamp is illumi-

nated, and means for controlling each end signal and the signal relay for the adjacent intermediate signal by the track relay at the opposite end of the stretch and for controlling each end signal also by the adjacent track relay.

In testimony whereof I affix my signature in presence of two witnesses.

HENRY W. GRIFFIN.
